(57) **CLAIM**

The ornamental design for the bench, as shown and described.

DESCRIPTION

FIG. 1 is a perspective view of a bench;

FIG. 2 is a top view thereof;

FIG. 3 is a front elevational view thereof;

FIG. 4 is a right side elevational view thereof, where the left side elevational view is a mirror image thereof;

FIG. 5 is a rear elevational view thereof; and,

FIG. 6 is a perspective view of a second embodiment of a bench, portions of which are cut away to illustrate indeterminate length which is the sole difference between it and FIGS. 1 through 5.

1 Claim, 4 Drawing Sheets
